John Rogers.

Mar. 1597

John Rogers, of New York, N.Y.
Letters Patent No 1597, dated May 27-1862.

The schedule referred to in these Letters Patent and making part of the same.

To all whom it may concern,

Be it known that I, John Rogers, of the City and State of New York, have invented or produced a new and original design for a group of Statuary, and I do hereby declare that the following is a full and exact description of the same.

The group is called the camp fire, and consists of two figures A and B. The figure A, represents a negro. His right foot C, rests on the ground D, his left foot E, is on the rock F, in his right hand G, he holds a ladle H, and stirs the contents of the kettle I, his left arm K, rests on the bar L, in his left hand M, he holds the lid N, of the kettle I, his shirt sleeves are rolled up and he is listening to figure B, who is reading a newspaper O.

Figure B, is seated on a basket P. His left leg Q, is crossed over his right leg R, his left hand S holds the paper O. His right hand T, clasps his leg Q, and his foot U, is turned towards the fire V, his overcoat W, hangs on the crooked stick X, his gun Y, rests in the same place.

Figure B, is dressed in soldiers clothes.

Having thus described my invention what I claim and desire to secure by Letters Patent, is a design for a group of Statuary as herein fully described and shown.

Witnesses.
